Des. 218,823

Patented Sept. 29, 1970

218,823

FISHING FLY RETRIEVER

Charles A. Richins, 8104 Peerless Ave.,
Orangevale, Calif. 95622

Filed July 3, 1969, Ser. No. 18,047

Term of patent 14 years

Int. Cl. D22—08

U.S. Cl. D22—31

FIG. 4

FIG. 1

FIG. 2

FIG. 3

FIG. 5

FIG. 1 is a front elevational view of my new design for a fishing fly retriever;

FIG. 2 is a side elevational view thereof as viewed from the right of FIG. 1;

FIG. 3 is a rear elevational view thereof;

FIG. 4 is an end elevational view as viewed from the top of FIG. 1; and

FIG. 5 is an end elevational view as viewed from the bottom of FIG. 3.

I claim:

The ornamental design for a fishing fly retriever, substantially as shown.
